Fig. 4

FIGURE 1 is a plan view of a traffic light signal in a preferred embodiment of my new design,

FIGURE 2 is a front elevation of the preferred embodiment,

FIGURE 3 is a rear elevation of the preferred embodiment,

FIGURE 4 is an end view of the preferred embodiment,

FIGURE 5 is a plan view of a traffic light signal in another embodiment of my new design,

FIGURE 6 is a front elevation of the embodiment of FIGURE 5,

FIGURE 7 is a rear elevation of the embodiment of FIGURE 5, and

FIGURE 8 is an end view of the embodiment of FIGURE 5.

The support arm is broken away in the views to indicate intermediate length.

This application is a continuation of my earlier filed co-pending applications, Serial Nos. D. 70,847 and D. 70,848, both filed July 9, 1962 and now abandoned.

I claim:

The ornamental design for a traffic light signal, as shown and described.
